CLAIM

The ornamental design for a nasal spray bottle as shown and described.

DESCRIPTION

FIG. 1 is a top perspective view of a nasal spray bottle according to the invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is top perspective view of a nasal spray bottle according to the invention with a cap engaged thereon;

FIG. 9 is a front view with a cap engaged;

FIG. 10 is a back view with a cap engaged;

FIG. 11 is a right side view with a cap engaged;

FIG. 12 is a left side view with a cap engaged;

FIG. 13 is a top view with a cap engaged.

FIG. 14 is a perspective view of a nasal spray bottle according to the invention with a top or sprayer portion thereof separated from a bottom or container portion thereof with a cap engaged on the top or sprayer portion;

FIG. 15 is a perspective view of a nasal spray bottle according to the invention with a top or sprayer portion thereof separated from a bottom or container portion thereof without a cap engaged on the top or sprayer portion;

(Continued)

FIG. 16 is a bottom view of the top or sprayer portion of a nasal spray bottle according to the invention, said top or sprayer portion being separated from the bottom or container portion;

FIG. 17 is a top view of the bottom or container portion of a nasal spray bottle according to the invention, said bottom or container portion being separated from the top or sprayer portion; and,

FIG. 18 is a perspective view of the bottom or container portion of a nasal spray bottle according to the invention being separated from a top portion, said bottom or container portion being separated from the top or sprayer portion. The broken lines in the drawings and the areas within them depict portions of the nasal spray bottle that form no part of the claimed design.
